UNITED STATES PATENT OFFICE.

FRANK H. BANCROFT, OF GARDNER, MASSACHUSETTS, ASSIGNOR TO P. DERBY & COMPANY, OF GARDNER, MASSACHUSETTS, A CORPORATION OF MASSACHUSETTS.

JOINT.

1,391,163.

Specification of Letters Patent. Patented Sept. 20, 1921.

Application filed May 24, 1919. Serial No. 299,500.

To all whom it may concern:

Be it known that I, FRANK H. BANCROFT, a citizen of the United States, and resident of Gardner, in the county of Worcester and 5 State of Massachusetts, have invented new and useful Improvements in Joints, of which the following is a specification.

This invention relates to joints and more particularly to joints between two wooden 10 members. The invention is peculiarly adapted for use in the manufacture of articles of furniture which comprise supporting legs and rounds, or a seat, supporting legs, rounds, back pillars or other wooden members, and 15 for the purpose of illustration the invention is herein shown and described in connection with such articles of furniture. It is, however, to be distinctly understood that the description of my improved joint as applied 20 to an article of furniture is illustrative only and that its utility is by no means limited to the specific example shown.

In the manufacture of wooden articles such as chairs it has heretofore been difficult to secure the various members together 25 in such manner as to withstand the rack and strain to which such articles are customarily subjected. The strength of the usual glued socket joint by means of which 30 the back pillars, legs and rounds of a chair are joined to the seat and to each other, depends upon the tightness of the joint between the socket member and the member fitting therein and the adhesion of the glue 35 employed. Under customary conditions of use, the wood in the chair quickly dries out in the dry atmosphere of the room causing a shrinkage of the wood and a consequent loosening of the joint. As soon as the chair 40 is subjected to a severe strain the members separate at the joint and unless repaired the chair quickly goes to pieces.

The principal object of the invention is to provide an improved socket joint for 45 curing the wooden members of furniture and similar articles together which will hold under severe usage, and which is easily and economically made, entailing no additional labor in the manufacture of the article.

50 In order to more clearly set forth the nature of my invention I have illustrated one

embodiment thereof in the accompanying drawing in which,—

Figure 1 is a side elevation partly in section of a stool showing the seat and a round 55 secured to the leg by means of the improved joint of this invention;

Fig. 2 is a detail sectional view through a joint between a chair leg and a round;

Fig. 3 is a section taken on line 3—3 of 60 Fig. 2; and

Fig. 4 is a section of a modified form of joint.

The stool illustrated in Fig. 1 comprises a seat 1 supported by legs 2 which are connected by rounds 3. The underside of the seat is provided with sockets 4 into which the upper ends of the legs 2 are driven. The base of each socket is provided with a tubular wedge-shaped ridge of wood 5 integral 65 with the seat, which may be conveniently formed by boring the socket 4 with a boring tool so constructed as to bore the socket leaving the tubular ridge of wood. 70

The upper end of the leg 2 which is adapted to fit into the socket 4 is provided with an annular kerf 6 of less width than the base of ridge 5, but of substantially the same depth as said ridge. This kerf may be made on a lathe during the process of turning the 75 leg, may be sawed in by an annular kerfing saw, or formed in any other suitable manner.

The round 3 is joined to the leg 2 in a similar manner, the leg being provided with a 85 socket 7 having a wedge-shaped ridge of wood 8 formed integrally on the base of the socket, which cooperates with an annular kerf 9 cut in the end of round 3.

In securing the leg 2 to the seat 1, the leg 90 is inserted into the socket opening and driven inwardly until the end of the leg becomes seated on the base of the socket. As the leg enters the socket, the point of wedge 5 enters the kerf 6 so that further inward driving of the leg forces the annular wedge into kerf 6 95 spreading or expanding the top of the leg to fill the socket.

The rounds 3 are wedged into sockets in the legs 2 in a manner similar to that in 100 which the legs are secured to the seat. The socket 7 is bored into the side of the leg

across the grain of the wood, and thus the grain runs transversely through the tubular ridge 8, while the kerf 9 is cut with the grain into the end of round 3. Referring to Fig. 3, 5 wherein the grain of the wood in the leg 2 is indicated by the longitudinal shade lines, it will be evident that the tubular wedge 8 will be far more compressible at point 10 where the compressive force is applied 10 against the side of the fibers of the wood, than at point 11 where the compressive force is applied against the ends of the fibers. The result is that the greatest wedging action 15 takes place at point 11 and the strain is transmitted longitudinally of the leg and the least wedging action takes place at point 10 where any great strain would tend to split the leg.

The socket may be tapered as shown at 12 20 in Fig. 4, by cutting the socket with an increasingly larger diameter toward its base. The base of the socket is provided with a tubular wedge 13, whose inner wall 14 is perpendicular to the base of the socket and 25 whose outer wall 15 has a taper greater than the taper of the wall of the socket. When the leg 2 is driven into socket 12 the wedge 13 expands the end of leg 2 until the tapered socket is filled. An exceedingly strong joint 30 is thus secured.

By the construction above described the socketed joints between wooden members may be readily and economically made, and through the inherent character of the tubular wooden wedge, a wedged joint secured 35 without danger of splitting either of the joined members.

I claim:

1. A joint for wooden articles comprising 40 a wooden member having a socket, a tubular ridge of wood projecting integrally from the base of said socket, and a second wooden

member having an annular kerf therein, said second member being adapted to fit into said socket, the said ridge coöperating with said kerf to expand the end of said second member in said socket. 45

2. A joint for wooden articles comprising a member having an undercut socket cut therein across the grain of the wood in such a manner as to leave an integral tubular ridge projecting from the base of the socket, and a second member having a kerf formed in the end thereof and running with the grain of the wood, said second member being adapted to fit into said socket, the said ridge coöperating with said kerf to expand the end of said second member in said socket. 50 55

3. A joint for wooden articles comprising a member having a socket cut therein across 60 the grain of the wood in such a manner as to leave a tubular ridge projecting from the base of the socket, and a second member having a kerf formed in the end thereof and running with the grain of the wood, said 65 second member being adapted to fit into said socket, the said ridge coöperating with said kerf to expand the end of said second member in said socket.

4. The method of joining wooden members which consists in forming an undercut socket in one of the members in such manner as to leave an integral tubular wedge protruding from the bottom thereof, cutting an annular kerf in the end of the other 70 member into which the wedge of the first member may enter, and forcing the members together so that the wedge of the first member enters the kerf of the second member 75 expanding the end of the second member 80 in the socket of the first member.

Signed by me at Boston, Mass., this 20th day of May, 1919.

FRANK H. BANCROFT.
